US00D838844S

(12) **United States Design Patent** (10) **Patent No.:** **US D838,844 S**
(45) **Date of Patent:** **** Jan. 22, 2019**

(54) **CATHETER**

(71) Applicant: **Coloplast A/S**, Humlebaek (DK)

(72) Inventor: **Mads Hindhede Svanegaard**,
Bagsvaerd (DK)

(73) Assignee: **Coloplast A/S**, Humlebaek (DK)

(**) Term: **15 Years**

(21) Appl. No.: **29/624,548**

(22) Filed: **Nov. 2, 2017**

(57) **CLAIM**

The ornamental design for a catheter, as shown and described.

DESCRIPTION

FIG. 1 is a perspective view of the catheter with the connector in a connected condition showing the new design; FIG. 2 is a front elevation view thereof; FIG. 3 is a back elevation view thereof; FIG. 4 is a left side elevation view thereof; FIG. 5 is a right side elevation view thereof; FIG. 6 is a top plan view thereof; FIG. 7 is a bottom plan view thereof; FIG. 8 is a perspective view of the catheter with the connector in an unconnected condition; FIG. 9 is a front elevation view thereof; FIG. 10 is a back elevation view thereof; FIG. 11 is a left side elevation view thereof; FIG. 12 is a right side elevation view thereof; FIG. 13 is a top plan view thereof; FIG. 14 is a bottom plan view thereof; and, FIG. 15 is another perspective view thereof.

In FIG. 1 the broken lines illustrate a package for containing a catheter and form no part of the claimed design.

In FIGS. 8-10, 12, and 15 a catheter portion is illustrated in broken lines that form no part of the claimed design.

In FIGS. 1-3, 5, 8-10, 12, and 15 a directional indicator formed on a connector is illustrated in broken lines that form no part of the claimed design.

1 Claim, 15 Drawing Sheets
